UNITED STATES PATENT OFFICE.

MATT A. O'BRIANOVICH, OF TABASCO, COLORADO.

LOCK.

Application filed July 28, 1924. Serial No. 723,803.

This invention relates to an improved lock which is principally, although not necessarily, designed for use in conjunction with a railway switch operating and signalling device.

It is my object to improve upon locks by providing one which is exceedingly simple and inexpensive and which is indeed well designed for the particular purpose for which it is intended.

A further object of the invention is to produce a well designed lock structure wherein the parts are so arranged as to provide a very sturdy structure and one which does not invite tampering owing to the inaccessibility of parts.

Other features and advantages of the invention may become apparent from the following description and drawing.

In the accompanying drawing forming a part of this specification, and in which like numerals are employed to designate like parts throughout the same:

Figure 1 represents a side elevation of a railway switch operating device, showing the manner in which my improved lock is associated therewith.

Figure 2 is a top plan view of Figure 1.

Figure 3 is an enlarged view partly in elevation and partly in section showing the construction of my improved lock and manner in which it is associated with the switch retaining means.

As before stated, the improved lock is especially, but not necessarily, intended for use in connection with railway switch operating and retaining means. Therefore, in order to give an idea of the manner in which the lock may be associated with such means, I have shown the same in the drawing. A pair of spaced railway and supporting ties are represented by the characters T. Positioned between these is a switch operating rod R which is connected with a vertically disposed rotatably mounted shaft S. This shaft extends through a discular plate P, supported in any suitable manner. That portion of the shaft above the plate is flat-faced as seen in Figure 2, and an angular

retaining member M is secured to the shaft and rotates above the plate. A lever is carried by the bend of the member M and is adapted to be selectively seated in one of the notches N. The lever is so proportioned with respect to the upturned end of the member M to permit it to be swung in a manner

to project the apertured locking tongue L thereon through an opening in the top portion of the member M. It is with this locking tongue that my improved lock is adapted to be associated, so that when the lever is seated in one of the aforesaid notches, the device will absolutely be locked by my improved key-controlled lock.

The improved lock comprises a suitably shaped casing 1 provided on opposed side walls with vertically disposed guides 2 in which a locking bolt 3 is slidable. This locking bolt is adapted to be projected through and beyond the opening in the aforesaid tongue L, to prevent retraction of the latter. The upper end of the bolt is adapted to be received between the lug 4 and the front wall of the casing. This arrangement assures rigidity of structure. A horizontal portion 5 is connected with the lower end of the bolt and one end of a coiled spring 6 bears upon this horizontal portion for automatically retracting the locking bolt. Extending downwardly from the portion 5 is a depending leg or guide 7 which is freely movable through an opening in the bottom of the casing. This depending portion 7 is formed adjacent its free end with a notch 8 into which one edge of the opening in the slidable tumbler plate 9 is received. This plate is provided on its top with a shoulder 10 to permit a key 11 to be engaged therewith for moving the tumbler in one direction. A spring 12 bears against an adjacent end of the tumbler and serves to move the same in the opposite direction for maintaining it engaged with the part 7 of the locking bolt. The casing is, of course, provided in its front wall with an opening to permit insertion of the locking tongue L, after which the locking bolt may be projected through the opening therein.

In practice, the key 11 is turned in a direction from left to right to slide the tumbler plate 9 in a corresponding direction against the action of the spring 12. When the tumbler plate is disengaged from the notch 8, the spring 6 serves to force the bolt and portions 5 and 7 downwardly, the last named portion being projected outwardly through the opening in the bottom of the casing. Normally, however, the free end of the portion 7 is flush with the bottom when the parts are in locked position. This prevents tampering with the internal mechanism of the lock. Of course, to set the lock again,

it is necessary to press the finger against the lower end of the guide 7 to force the locking bolt inwardly against the action of the spring 6. As soon as the bolt is forced 5 in a predetermined extent, the tumbler snaps into the notch 8.

Although I have shown and described the preferred and specific embodiment of the new lock, I wish it to be understood that 10 minor changes coming within the scope of the appended claim may be resorted to if desired. Also, I wish to emphasize the fact that while I have shown the lock applied to a specific kind of device, I wish it to be 15 understood that it can be used with other devices.

I claim:

A lock comprising a casing having an opening formed in its front for passage of 20 the part to be locked, guide strips secured to the interior of the side walls of the casing and disposed in spaced parallelism to the front wall, a locking bolt slidably mounted

in the guideways formed between the guide strips and said front wall, the lower end portion of said bolt extending rearwardly at right angles, a spring mounted in the casing and cooperative with said angularly directed end portion of the bolt for moving the latter normally downward, an integral 25 depending guide stem connected with the right angular portion of the bolt and having its free end projectible thru an opening in the bottom of the casing, a tumbler plate slidably arranged in the casing upon the interior of the bottom of the latter and engageable with a notch formed in said guide stem, a shoulder on said tumbler plate with which a key is adapted to be engaged for moving the plate in one direction, and spring 30 means in the casing and acting on the plate for moving it in an opposite direction.

In testimony whereof I affix my signature.

MATT A. O'BANOVICH.
